UNITED STATES PATENT OFFICE

148,601

DESIGN FOR A FILTER FOR COFFEE MAKERS

Wesley R. Becher, Wethersfield, Conn., assignor to The Silex Company, Hartford, Conn.

Application March 26, 1946, Serial No. 127,967

Term of patent 14 years

(Cl. D44—26)

To all whom it may concern:

Be it known that I, Wesley R. Becher, a citizen of the United States, residing at Wethersfield, in the county of Hartford and State of Connecticut, have invented a new, original, and ornamental Design for a Filter for Coffee Makers, of which the following is a specification, reference being had to the accompanying drawing, forming part thereof.

The essential features of the design reside in the parts shown in full lines.

I claim:

The ornamental design for a filter for coffee makers, substantially as shown and described.

WESLEY R. BECHER.
